UNITED STATES PATENT OFFICE.

STEPHEN MOGYORÓS AND STEPHEN VISI, OF EAST PITTSBURGH, PENNSYLVANIA.

FIREPLACE.

Application filed November 19, 1926. Serial No. 149,404.

The object of this invention is to provide a fire place construction in which the main chamber is divided by a vertical wall so that the equivalent of two grates and fire chambers are used, and arrangements are made for conducting smoke and products of combustion from a newly placed body of fuel to the ash pit below fuel in active combustion, on the other side of the apparatus, for the purpose of consuming the smoke and gases as they pass upwardly through the grate and fire toward a point of discharge.

A further object is to provide, in connection with a twin fire place construction, a centrally located flue, one end of which may be placed in communication with an ash pit below either grate, and an upper or oppositely located pipe connection for communication with the flue and being capable of being shifted and placed in communication with either fire chamber, so that the smoke from a newly placed body of fuel may be transferred to the other fire and there consumed. The principle is of general application.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 is a view of the fire place structure in front elevation.

Figure 2 is a side elevation.

Figure 3 is a top plan view.

Figure 4 is a view in vertical section.

Figure 5 is a section on line 5-5 of Figure 4.

Figure 6 is a section on line 6-6 of Figure 4.

Figure 7 is a section on line 7-7 of Figure 4.

Figure 8 is a vertical section, on a reduced scale, showing the circulation of heated air and products of combustion.

Figure 9 is a view in front elevation, showing a modified form.

Figure 10 is a vertical longitudinal section, on line 10-10 of Figure 9.

Figure 11 is a vertical transverse section on line 11-11 of Figure 10.

Figure 12 is a fragmentary view in horizontal section, on line 12-12 of Figure 11.

Figure 13 is a vertical transverse section on line 13-13 of Figure 10.

In the form shown in Figures 1 to 8 inclusive the front wall of a casing or housing is designated 10, the side walls are shown at 11 and 12, and a rear wall 13 includes or has formed therewith an outwardly extending portion 14 providing a duct or smoke flue 15. The upper portion of the housing is closed by a cover 16 carrying thereon a pipe connection 17 for the accommodation of a flue 18.

Fire chambers such as 20 are defined between front wall 10 and vertical wall 21, and these fire chambers are separated by a central vertical wall 22. A grate such as that shown at 23 is mounted in each side of the housing and on opposite sides of wall 22, and the lining for the fire box, on each side, is shown at 24. Access to the fire chambers is obtained through doors 25, and doors 26 provide access to the ash pit 27, below the grate.

An opening 28 communicates with the ash pit 27, on each side of the vertical partition wall 22, and a damper 29 is hinged at 29', in line with wall 22 and is adapted to close openings 30 and 31, one opening being closed at a time, under the conditions indicated below. In the closing movement the damper 29 contacts with ribs or elements 30' and 31'.

A transverse wall 33 is provided with openings at 34 and 35, positioned respectively above the fire chambers 20, and a curved or U-shaped pipe 36, sometimes termed a switch pipe is mounted on a plate 37, the ends of the pipe extending through the plate and one end of the pipe 36 being adapted to project downwardly into flue 15, and the pipe being adapted to swing with reference to said flue. The plate 37 and the U-shaped pipe 36 are rigidly connected, and move together from the full line position of Figure 5 to either dotted line position, so that the pipe 36 at its front portion may be caused to register with either opening 34 or 35, for the purpose of establishing communication between either fire chamber 20 and flue 15. Stops 38 limit the movement of the plate 37 in either direction, and this plate, together with U-shaped pipe 36, is shifted by a pin, handle, or operating element 40, and in order to operate the damper 29 at the same time, I provide a bracket 41 fixed at 42 with reference to the pipe 36 and the pin

40 and including an offset portion 43 engaging a crank end 44 of rod 45. A lower crank element 46 on rod 45 engages an arm 47 of operating member 48 controlling damper 29.

5 In the use of the apparatus, it may be assumed that the fire above grate 23 at the left of Figure 8 has been supplied with new fuel, and the products of combustion, or smoke, pass in the direction shown by the arrows, 10 through pipe 36 and flue 15, to the ash pit 27, at the right, damper 29 having been properly positioned by the operation of handle 40. The smoke will then pass upwardly through the grate and through the body of fuel on that side of the apparatus, and of central vertical partition 22, the smoke being consumed by the coked fire on that side, and the draft will be upwardly through the 15 point of discharge, indicated at 18. The opening 35 permits of direct communication between the fire chamber or combustion chamber at the right in Figure 8, and the upper portion of the housing, under the conditions shown in the view referred to.

20 25 When fuel is to be added to the fire on the right side of central vertical partition 22, the U-shaped pipe 36, or switch pipe, is shifted by handle 40, so that the pipe will establish communication with opening 35, 30 and in this operation, the damper 29 will establish communication between ash pit 27 at the left and the vertical flue 15. It will be observed therefore, that elements 29 and 36, representing the lower damper, and the 35 U-shaped pipe, are reversely controlled, that is pipe 36 establishes communication with the left-hand combustion chamber 20 and the damper 29 establishes communication with the right-hand ash pit 27. When handle 40 is shifted there is communication between the right-hand combustion chamber 20 and the left-hand ash pit 27.

40 45 In Figures 9 to 13, showing a modification, a central vertical wall 50 separates combustion chambers or fire chambers 51, and either one of the upper longitudinal ducts 52 may be placed in communication with lower duct or pipe 53 by means of U-shaped pipe or switch 54, adapted to swing with 50 reference to pipe or duct 53, and being mounted on plate 55 controlled by rod 56, and the plate being guided by segmental arm 57 having its ends secured at 58 to transverse vertical wall 59. The mounting of U-shaped pipe 54, at its lower end is equivalent to a pivotal mounting, and the pipe swings from the position of Figure 13 to a position in which it may establish communication between the upper right-hand pipe or duct 52 and the lower duct 53.

55 60 Suitable grates 59 are positioned above separate ash pits 60, on opposite sides of vertical wall 50 and a damper 61 establishes communication between either ash pit and lower duct 53, depending upon which of the

65 draft doors 62 is open. These doors are connected by chains 63 with opposite sides of damper 61.

70 The products of combustion and heated air from that fire chamber or combustion chamber 51 containing a newly burning body of fuel may therefore be conducted below the grate 59 on the opposite side of the apparatus, either flue 52 and the lower duct 53 being employed for that purpose by an obvious control of front damper 61 and rear U-shaped pipe 54. New fuel being added above the grate just mentioned, the draft will be through the other pipe 52, through chamber 65 and exhaust or discharge connection 66. The fuel is introduced through either of the doors 67, depending upon 75 which side of the apparatus requires firing.

80 Having described the invention what is claimed is:—

85 1. In a structure of the class described, a plurality of combustion chambers, a fire box below each chamber and an ash pit below each fire box, a smoke flue, and means for placing the lower end of the smoke flue in communication with either ash pit, a pipe adapted to swing with reference to the upper end of the flue, a swinging plate on which the plate is mounted, and means for shifting the plate and pipe to position for establishing communication between the flue and either combustion chamber.

90 95 2. In a structure of the class described, a plurality of combustion chambers, a fire box below each chamber and an ash pit below each fire box, a smoke flue, and means for placing the lower end of the smoke flue in communication with either ash pit, a pipe adapted to swing with reference to the upper end of the flue, a swinging plate on which the pipe is mounted, and means for shifting the plate and pipe from one combustion chamber to the other and simultaneously controlling the means for placing the lower end of the flue in communication with 100 one of the ash pits, to the exclusion of the other.

105 110 3. In a structure of the class described, a plurality of combustion chambers, a fire box below each chamber, an ash pit below each fire box, a smoke flue, means for placing one end of the smoke flue in communication with either ash pit, a pipe adapted to swing with reference to one end of the flue and communicating therewith, a swinging plate on which the pipe is mounted, a division wall in the structure, the fire chambers being in communication with spaced openings in the wall, and means for shifting the plate and pipe to position for establishing communication between the flue and either of said openings.

115 120 125 4. In a structure of the class described, a plurality of combustion chambers, a fire box below each chamber, an ash pit below each

fire box, a smoke flue, means for placing one end of the smoke flue in communication with either ash pit, a pipe adapted to swing with reference to one end of the flue and communicating therewith, a swinging plate on which the plate is mounted, a division wall in the structure, the fire chambers being in communication with spaced openings in the wall, and means for shifting the plate and pipe to position for establishing communication between the flue and either of said openings, and controlling devices governing the means for placing the flue in communication with one of the ash pits, simultaneously with the shifting of the plate and pipe. ¹⁵
